ATTORNEY

UNITED STATES PATENT OFFICE.

FREDERICK J. HOYT, OF NEW YORK, N. Y.

ORE-FURNACE.

SPECIFICATION forming part of Letters Patent No. 272,959, dated February 27, 1883.

Application filed April 28, 1882. (No model.)

To all whom it may concern:

Be it known that I, FREDERICK J. HOYT, a citizen of the United States, residing at New York, in the county of New York and State of New York, have invented certain new and useful Improvements in Furnaces for Desulphurizing Ores, of which the following is a specification, reference being had therein to the accompanying drawings.

The object of the present invention is to provide a furnace for rapidly and thoroughly desulphurizing ores; and this object I attain by the novel and improved construction of parts hereinafter described, and pointed out in the claim.

The accompanying drawings illustrate a mode of carrying out my invention.

Figure 1 is an exterior view of a furnace embodying my improvements. Fig. 2 is a vertical sectional view of the same. Fig. 3 is a horizontal section taken on the line xx of Fig. 2.

A represents the furnace, having a fire-box, B, near the bottom, and a horizontal flue, C, near the top. Immediately above the fire-box B is an inclined plane, D, extending from the interior of the furnace, near one wall thereof, to the exterior through the opposite wall. The central portion of the furnace from top to bottom is occupied by plates or platforms E, arranged in pairs, so as to swing downward, like trap-doors. The flue f, leading from the fire-box to the top of the furnace, is built in alternate opposite walls, so as to cause the products of combustion to pass successively under and over the plates or platforms E before reaching the final exit. These plates or platforms are so arranged with relation to the flue that one platform has one edge toward the flue and the next one above or below has the opposite edge toward the flue. Each platform E is composed of two halves, arranged to swing downward, like trap-doors, and to join each other when in a horizontal position. Each door or plate is carried by a rock-shaft, G, having its bearings in the walls of the furnace, at right angles to the walls in which the flue f is built. One end of each rock-shaft extends beyond one wall of the furnace, and is bent horizontally at a right angle with the main portion, and carries a weight, H, sufficient to counterbalance the weight of the plate or door. The other end of the shaft extends

beyond the opposite wall of the furnace, and carries a snail-cam, J. Near each cam a pawl, K, is pivoted, on the other wall of the furnace, so that its lower end will engage the shoulder of the cam. There being two halves or doors to each platform, and each half or door having its shaft provided with a cam, the pawls K are arranged in pairs, and each pair is so inclined that while the lower ends or points of the pawls engage with the cams the upper ends are nearly in contact with each other. On the other wall of the furnace are a number of pulleys, L, one of which may have motion imparted to it from any suitable source and at any desired speed. Around these pulleys passes an endless belt, M, which carries a tapering or wedge-shaped block, P. The horizontal flue C, near the top of the furnace, is provided with two transverse semi-partitions, ee², one extending upward from the bottom of the flue and the other extending downward from the top of the flue, and between them, in the top of the flue, is an opening provided with a removable cover, s. Above this flue may be any desired number of plates or platforms E. As here shown, there are two of said platforms above said point.

The operation of my invention is as follows: The ore to be desulphurized is deposited in the furnace through a hopper, Q, at the top, in successive quantities, each deposit of ore being sufficient to just cover the platform to a suitable thickness to enable the flame to act on the ore. All the platforms being supplied with ore, the flames from the fire-box pass successively under and over each of the platforms and through the ore deposited thereon until they reach the flue C, where they pass out of the furnace. Motion being imparted to the belt M, the block P, as it ascends, passes successively between the pawls of each pair, separating their upper ends and disengaging their lower ends from the cams J. This allows the weight of the ore on the platform to separate the two halves thereof and to cause them to swing downward and deposit the ore on the next lower platform, or on the inclined plane D, as shown in Fig. 2. When the lowest platform is thus emptied, the weights H restore it to its closed position, where it is held by the engagement of the pawls with the cams, so as to be ready to receive the contents of the next higher platform when the same shall be opened.

by the action of the block P on the pawls K, as above described, and this action is repeated until the highest platform is reached.

By this construction, arrangement, and operation of the parts, the ore is thoroughly stirred and turned over and over, so as to subject all parts of it to the action of the flames. If any particles of metal should be carried into the flue C, they are arrested by the semi-partitions ee^2 and deposited between them, whence they may be removed through the opening covered by the cap or covers.

What I claim as new, and desire to secure by Letters Patent, is—

The combination, with the plates E and rock-shaft G, provided with weights H and cams J, of the pawls K, belt M, and wedge or block P, all substantially as shown and described.

In testimony whereof I affix my signature in presence of two witnesses.

FREDERICK J. HOYT.
